UNITED STATES PATENT OFFICE.

GEORGE G. TUGNOT, OF KLAMATH FALLS, OREGON.

DIRECTIONAL TRAFFIC SIGNAL.

Application filed February 12, 1925. Serial No. 8,830.

The present invention relates to signals designed chiefly for traffic to designate the intention of a driver to make a turn to the right or to the left or to reduce the speed 5 of a vehicle or to bring the same to a stop whereby to avoid an accident and obviate confusion, the signal being designed to be mounted conspicuously upon the vehicle so as to be readily seen from the rear or in 10 front.

Other objects and advantages will be apparent and suggest themselves as the nature of the invention is understood.

While the drawings illustrate an embodiment of the invention it is to be understood that in adapting the same to meet different conditions and requirements, various changes in the form, proportion, and minor details of construction may be resorted to without 20 departing from the nature of the invention.

Referring to the accompanying drawings forming a part of the specification,

Figure 1 is a front view of a signal embodying the invention,

Figure 2 is a reverse view of the signal showing the letters formed by perforations instead of being stenciled,

Figure 3 is a transverse sectional view on the line 3—3 of Figure 1, and

Figure 4 is a detail sectional view on the line 4—4 of Figure 1.

Corresponding and like parts are referred to in the following description and designated in the several views of the drawings by like reference characters.

The signal comprises a casing 1 of sheet metal or other suitable material which is subdivided by a vertical longitudinal partition 2 and horizontal partitions 3 forming 40 a plurality of pairs of compartments 3^a and 3^b horizontally arranged. The outer walls of said compartments are provided with directional data cut therein either by being stenciled as shown most clearly in Figure 1, or perforated as indicated in Figure 2. The partition 2 terminates some distance from the adjacent end of the casing and is cut

away as indicated at 4 to provide ample clearance for an electric bulb 5 opposite each pair of compartments 3^a and 3^b which is provided to illuminate the signal and clearly display the directional data which may be such as to indicate a left turn, a right turn, slow and stop, it being understood that each signal will be complete in 55 itself and bear the proper designating data, the several signals being placed in vertical position and located conspicuously to insure observation from the rear and in front of the vehicle. A cap 6 closes one end of the casing and is provided with the electric bulb 5, the latter being included in a circuit (not shown) which is controlled by means of a switch. When a plurality of signals are provided a gang switch will be employed 60 for controlling the several light circuits so that the proper signal may be displayed to indicate the intention of the driver to make a turn either to the right or to the left, or to reduce the speed of the vehicle or to bring 65 the same to a stop.

What is claimed is:—

A signal of the character specified comprising an elongated casing closed at all sides and at one end, whereby one end only 75 will be open, a vertical partition within said casing having flanges at its top and bottom directly engaging the top and bottom walls of the casing, transverse partitions extending from the vertical partition and intimately engaging the side walls of the casing, 80 said partitions providing signal spaces, the side walls of the casing being directly perforated opposite the spaces, the perforations alone constituting signals, a cap removably 85 telescoping over the open end of the casing, lamps carried by the cap extending into the casing, and the vertical partition at the adjacent end being cut away intermediate the transverse partitions to accommodate the 90 lamps whereby each lamp will illuminate two spaces.

In testimony whereof I affix my signature.
GEORGE G. TUGNOT.
